UNITED STATES PATENT OFFICE.

HENRY COLE, OF DENVER, COLORADO.

WATER-ELEVATOR.

1,072,430.

Specification of Letters Patent.

Patented Sept. 9, 1913.

Application filed September 5, 1911. Serial No. 647,702.

To all whom it may concern:

Be it known that I, HENRY COLE, a citizen of the United States, residing in the city and county of Denver and State of Colorado, have invented certain new and useful Improvements in Water-Elevators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to certain improvements in water-elevators, over my United States Letters Patent issued to me November 27th, 1906, Number 836865.

The object of my invention resides in the construction of a water-elevator for quickly and effectively raising quantities of water for irrigation, and other similar purposes.

Another object of my invention resides in the provision, of mechanism for preventing the buckets from being carried downwardly into the well under the influence of the extra weight incident to the quantity of water contained in the buckets on the upward moving side of the conveyer, after the power for operating the conveyer has been discontinued.

The necessity for a cheap and efficient water-elevating machine has been keenly felt in arid districts where irrigation is necessary and where plenty of water is located a few feet below the surface. In these districts where there is seldom any rainfall, it is not unusual to find an ample supply of water underneath the surface, sufficient for

40 irrigating a considerable area surrounding the place where the well is sunk, and in such districts my water-elevating device will enable the water to be raised to the surface in a simple, inexpensive, and efficient manner.

45 Having set forth the objects of my improved water-elevator I will proceed to describe the same in detail, reference being made to the accompanying drawing in which is illustrated an embodiment thereof.

50 In the drawing:—Figure 1, is a side elevation of my improved water-elevator in position for use. Fig. 2, is a top plan view of my improved water-elevator. Fig. 3, is a top plan view of a trough employed in connection with my improved

water-elevator. Fig. 4, is an end view of a bucket employed with my water-elevator, illustrating the same attached to a fragment of the conveyer and showing the position the bucket occupies on the upward moving side of the conveyer. Fig. 5, is a similar view showing the position the bucket occupies on the downward moving side of the conveyer. Fig. 6 is a vertical section taken on the line 6—6 Fig. 1, looking in the direction of the arrow. Fig. 7 is a detail view of the U-shaped member for holding the brake in the inoperative position.

The same reference characters indicate the same parts in all the views.

Let the numeral 4 designate each of two suitable spaced endless sprocket-chains, engaging a pair of upper sprocket wheels 6, and a pair of lower sprocket wheels, only one of the latter being shown in the drawing and designated by the numeral 7. These chains 4 are connected by buckets 8, whose extremities are provided with spindles 9, journaled in lugs 10, mounted upon the chains. Each bucket is open at the top, and its bottom is of oval shape. The spindles 9 of each bucket are near the top of the latter, whereby the buckets have a normal tendency to occupy the vertical position, or a position with their open sides uppermost, since the bottom of the buckets is farther from the pivotal center than the top.

The upper sprocket wheels 6 are made fast to a shaft 12, suitably journaled on supports 13, secured to a frame-work 14 by means of bolts 15. The supports 13 are provided at their upper extremities with U-shaped slots 16, which receive the extremities of the shaft 12.

Upon the shaft 12, two suitably spaced disks 17 are made fast, the peripheries of which are successively engaged by the opposite extremities of the buckets, during the travel of the chains 4 composing the conveyer. These disks 17 act upon the buckets to cause the latter to turn upon their journals for dumping the water therefrom. As each bucket passes over the disks 17, and assume a position corresponding with the downward moving side of the conveyer, the same becomes tilted to a horizontal position, and stops, or pins 18, mounted on the buckets engage the chains 4 for maintaining the buckets in the horizontal position. Now as the buckets on the downward mov-

ing side of the conveyer, reach the lower sprocket wheels and begin to pass around the said wheels, the buckets occupy a position to scoop up water from the well, and as each 5 bucket assumes the upward moving side of the conveyer, the same finds its center of gravity, and turns upon its journals to the vertical position, or a position with its open side uppermost. Upon the opposite extremities of each bucket, and on the lower portion thereof, are mounted pins 19 which engage the chains 4 when the buckets are 10 in the vertical position, or on the upward moving side of the conveyer, whereby the buckets are held to a certain extent against 15 rocking during their upward travel.

Made fast to the opposite extremities of the shaft 12 are two drive-wheels 20, which respectively engage relative small wheels 21 20 suitably journaled as shown at 22. Each of the wheels 21 is provided with a groove 23 in its periphery into which grooves the peripheries of the wheels 20 respectively fit.

Mounted upon the frame work 14 on opposite sides thereof is arranged a brake mechanism, which, I will designate in its entirety by the reference character 24. This brake mechanism consists of a flat shoe 25, secured at one extremity to one 25 member 26 of an angle member, the other member 27 of the angle member being perforated. A rod 28 passes through the perforation of the member 27, the opposite extremity of the said rod being supported by 30 an angle member 29 secured to the frame-work 14. This rod 28 is mounted to have a sliding movement in the angle member or support 29, while the member 27 is rigidly secured to the rod 28. Interposed between 35 the member 27 and the member 29 and surrounding the rod 28, is a coil spring 30, which acts upon the member 27, to cause the shoe 25 to wedge in between the wheels 20 and 21, whereby a friction is created 40 sufficient to prevent, the buckets on the upward moving side of the conveyer, from causing backward travel of the said buckets under the influence of the weight of the water contained therein. In order to retain 45 the shoe 25 out of engagement with the wheels 20 and 21, I provide a member 31, which I insert between the head 32 of the rod 28, and the angle member 29, and since 50 the shoe 25 is connected to move with the rod, the said shoe is held out of engagement with the two wheels against the tension of the spring 30. This member 31 is provided 55 with a U-shaped part which straddles the rod 28. Now in order to set the brake it 60 is only necessary to remove the member 31 from between the head 32 of the rod and the member 29 whereby the spring acting on the member 27, causes the shoe 25 to move 65 into wedging engagement with the wheel 20 and 21 and thus prevent rearward move-

ment of the buckets after the driving power has been shut off.

On the top of the frame-work 14, I mount a specially constructed trough designated in its entirety by the reference character 33. 70 This trough is provided with a centrally located opening 34, on opposite sides of which are arranged parallel troughs 35 and 36 communicating with each other by means of channels 37. The buckets in their upward 75 travel pass through the opening 34 in the trough and as they pass over the disks 17 empty their contents into the trough 35, the water thence flowing in the direction of the arrows through the channels 37, into the 80 trough 36, from which it is discharged through a pipe 38, leading to any desired place.

An important feature of my invention essential to the effective operation of a water 85 elevator of this character will now be described.

By referring to Fig. 1, of the drawing it will be noted that the wheels 20 ride respectively upon the wheels 21 and that the 90 journals of the wheels 20 are supported slightly above the bottom of the journal boxes 16 as shown at 41, whereby the wheels 20 are permitted to rest entirely upon the wheels 21. The object of this construction is to lessen the resistance incident to friction usually present where many bearing parts are employed. By virtue of the construction heretofore described only a minimum amount of driving power is required for operating the elevator. The weight of the conveyer and buckets and also the water contained in the buckets on the upward moving side of the conveyer is supported entirely by the wheels 21, instead of 100 by the shaft 12, thus the friction incident to the journal of this shaft is entirely relieved from the journal box 16, and transferred to the wheels 20 and 21 which do away almost entirely with any friction. 110 Suitable ball-bearings 45 may be arranged in the frame 14 in engagement with the shaft 22 in order to relieve the friction from the shaft.

From the foregoing description, the use 115 and operation of my improved water-elevator will be readily understood.

Power is transmitted to my improved water-elevator through the medium of a belt 40, to a drive wheel 39 keyed upon the 120 shaft 12, whereby the shaft 12 is actuated to cause the endless chains 4 to travel over the upper sprocket-wheels 6, and lower sprocket wheels 7, carrying the buckets 8 therewith. The buckets 8 on reaching their upward 125 limit of movement, are caused to empty their contents in the trough 35, from which trough the water takes the course heretofore described. Now whenever the driving power is shut off, the brake 24 can be set as hereto- 130

fore explained, and thus the buckets on the upward moving side of the conveyor will be held against moving rearward.

I claim—

- 5   1. A water-elevator, comprising a pulley shaft, pulley wheels mounted on said pulley shaft, chains passing over said pulley wheels, buckets connecting said chains, a disk arranged adjacent each of said pulley wheels
- 10   on said pulley shaft, the extremities of said buckets being provided with pins adapted to engage the said chains when the buckets are on the upward moving side of said chains, other pins with which the extremities of said
- 15   buckets are provided adapted to engage the chains when the buckets are on the downward moving side of said chains.
2. An elevator, comprising a pulley, a conveyer passing over said pulley, buckets journaled upon said conveyer, the said buckets being provided with pins adapted to engage the conveyer when the buckets are on the upward moving side of the latter, other pins adapted to engage the conveyer when
- 25   the buckets are on the downward moving side of the latter, and means carried by the pulley and adapted to engage the said buckets to cause the latter to turn upon their journals for dumping the same.
- 30   3. An elevator, comprising an endless traveling conveyer, buckets journaled upon the said conveyer, the said buckets being
- provided with pins adapted to engage the conveyer when the buckets are on the upward moving side of the latter, other pins 35 adapted to engage the conveyer when the buckets are on the downward moving side of the latter, and disks adapted to be engaged by said buckets to cause the latter to turn upon their journals for dumping the 40 same, substantially as described.
4. An elevator, comprising a pulley shaft, sprocket wheels mounted upon said pulley shaft, sprocket chains passing over said sprocket wheels, buckets connecting said 45 sprocket chains and journaled on the latter, the said buckets being provided with pins adapted to engage the sprocket chains when the buckets are on the upward moving side of the latter, other pins mounted on said 50 buckets and adapted to engage the sprocket chains when the buckets are on the downward moving side of the latter, and disks mounted upon the said pulley shaft and adapted to be engaged by the buckets for 55 causing the latter to turn on their journals to the dumping position.

In testimony whereof I affix my signature in presence of two witnesses.

HENRY COLE.
